NONSURGE MEANS

Donald G. Griswold, Alhambra, Calif., assignor
to Clayton Manufacturing Company, Alham-
bra, Calif.

Application October 14, 1942, Serial No. 461,977

21 Claims. (Cl. 103—113)

1

This invention relates to liquid pumping systems wherein a quantity of air or gaseous fluid precedes the flow of liquid. More specifically, the invention relates to non-surge means for use in such systems, whereby all surging in the system due to starting of the pump is eliminated.

The pumping system of the present invention includes a deep well pump (which may be of the centrifugal type), a service check valve (which may be conventional) connected with the outlet of said pump and with a pipe line, a novel hydraulically operated non-surge valve also connected with the outlet of said pump and with the atmosphere, and automatic control means for effecting the opening and closing of said non-surge valve.

In pumping systems of the general character mentioned, when the pump is idle, air finds its way into the pump casing above the liquid level as well as the portion of the system between the pump and the check valve. In order to prevent surges in the system when the pump is again started, the sudden excess pressure built up by the pump in the line between the pump and check valve must be relieved until the inertia of the water in the main pipe line is gradually overcome. It is also desirable to eliminate the air (and sand in some instances) which is delivered when the pump is first started and prevent its introduction into the system.

The non-surge means comprising the present invention is adapted to be so associated with the pump and service check valve that it will automatically vent to the atmosphere the air or gaseous fluid which precedes the flow of liquid from the well when the pump is started. The control for the non-surge valve is arranged so that said valve is always open at the time that the pump is started. Consequently, there is no pressure between the pump and the check and non-surge valves. The pump, therefore, pumps the air into the atmosphere through the open non-surge valve before any water reaches said valve. In view of the fact that the resistance to the flow of water through the valve is much greater than the resistance to the flow of air, the flow of water through the non-surge valve is restricted and a hydraulic back-pressure is built up on the inlet side of said non-surge valve. This hydraulic pressure is utilized to operate a pressure-responsive device associated with a pilot valve which controls the admission and exhaust of operating liquid under pressure to the non-surge valve so as to control the opening and closing of said non-surge valve. The control means is such

2

that the non-surge valve is caused to close gradually so that liquid flow therethrough will taper off until the valve closes drip tight. As the pressure builds up on the inlet side of the non-surge valve it gradually overcomes the resistance to flow offered by the check valve and said check valve eventually opens to permit the liquid to be pumped directly into the pipe line. Thus, the non-surge valve does two things: First, it eliminates or vents all air or gas from the system, and second, it prevents all surging in the system due to starting the pump.

Another feature of the non-surge valve is that it can be constructed to serve as a pressure relief valve in the event that excessive hydraulic pressure is built up by the pump, as will appear more fully hereinafter.

The principal object of the invention is to provide non-surge means for use in pumping systems wherein a quantity of air or gaseous fluid precedes the flow of liquid.

Another object of the invention is to provide a pumping system in which all surges are eliminated due to the starting of the pump.

25 Another object of the invention is to provide an automatic non-surge valve which is normally open when the pump is started and gradually closes as the pump builds up hydraulic pressure on the inlet side of said valve, and which again opens after the pump has stopped, so that said valve is open to vent air upon the next starting operation of the pump.

Another object of the invention is to provide an automatic valve means that will serve the dual purpose of an air vent and a hydraulic pressure release.

Another object of the invention is to provide a non-surge valve and automatic control means therefor which will permit said valve to remain open as long as air is being pumped therethrough, effect closing of said valve upon pumping of liquid therethrough, and effect opening of said valve upon the building up of excessive pressure on the inlet side of said valve.

45 Another object of the invention is to provide a non-surge valve and automatic control means for said valve which will effect closing of said valve when a pre-determined hydraulic pressure is built up by the pump on the inlet side of said valve.

50 Still another object of the invention is to provide a non-surge valve having control means which will effect closing of said valve at a pre-determined rate, regardless of the rate at which pressure is built up by the pump.

55 A further object of the invention is to provide

a non-surge valve and control means which is responsive only to a predetermined hydraulic pressure on the inlet side of said valve.

A still further object of the invention is to provide a non-surge valve and control means for said valve including an adjustable element for varying the pressure at which closing of the non-surge valve can be effected.

Another object of the invention is to provide a non-surge valve including means for limiting the extent of opening of said non-surge valve to assure building up of hydraulic pressure sufficient to effect closing of said non-surge valve irrespective of the capacity of the pump with which it is associated.

Still another object of the invention is to provide a hydraulic pressure operable non-surge valve and control means for said valve including a pressure-responsive device and pilot valve actuated by said device, together with means for preventing the opening of said non-surge valve due to a momentary drop in pressure on the inlet side of said non-surge valve.

Other objects and features of the invention will be apparent from the following description taken in conjunction with the accompanying drawings, in which:

Fig. 1 diagrammatically illustrates a pumping system embodying a non-surge valve and control means constructed in accordance with the principles of the present invention;

Fig. 2 is an enlarged diagrammatic cross-sectional view of the non-surge valve and the automatic control means for said valve, said valve and control means being shown in the positions which they occupy when the pump is idle;

Fig. 3 is a view similar to Fig. 2 but showing the non-surge valve and the control means in the positions they occupy when the pump has built up sufficient hydraulic pressure on the inlet side of the non-surge valve to effect closing of said valve;

Fig. 4 is a sectional view taken on the line 4-4 of Fig. 3 and particularly illustrating the porting of the pilot disc of the pilot valve;

Fig. 5 is an enlarged plan view of a modified form of porting for the pilot disc which will adapt the non-surge valve of Figs. 2 and 3 to also serve as a hydraulic pressure relief valve; and

Fig. 6 is a fragmentary sectional view of a modified spring arrangement for use with a control device employing the pilot disc of Fig. 5.

Referring now to Fig. 1 of the drawings, the numeral 1 generally indicates a motor driven centrifugal pump which is mounted upon a well casing 1^a and connected by any suitable piping 2 with a non-surge valve 3 and control means for said valve generally indicated by the letters X and P. A conventional or known type of service check valve 4 has an inlet chamber 5 connected with the piping 2 and an outlet chamber 6 connected with a pipe line 7.

Referring now to Fig. 2, the non-surge valve 3 includes a body B, a cover C, and a circular diaphragm D whose marginal portion is clamped between the body B and the cover C by any suitable number of conventional stud bolts 12. The body B is provided with a substantially vertical partition wall 13 which cooperates with an inclined wall portion 14 to provide inlet and outlet chambers 15 and 16, respectively, in said body. The wall portions 13 and 14 are merged to provide a circular opening which is threaded and adapted to receive an annular valve seat 17.

The valve seat 17 is provided with a circular opening 18 through which water or other liquid can pass in traveling from the inlet chamber 15 to the outlet chamber 16. The valve seat 17 includes radial arms 19 which extend downwardly and terminate in a portion 20 which serves as a guide for the lower end of a valve stem 21. The lower extremity of the valve stem is reduced and shouldered to receive a washer 22 which forms a seat for one end of a compression spring 23. The opposite end of the spring 23 is received in a cavity 24 formed in a plug 25 threaded into the body B.

The cover member C is provided with a central boss portion 26 counterbored to receive a guide bushing 27 for the upper end of the valve stem 21. The guide bushing 27 is arranged so that it is in axial alignment with the guide portion 20 on the valve seat 17. The valve stem 21 carries follower plates 28 and 29 disposed on opposite sides of the diaphragm D. The valve stem 21 also carries a circular member 30 provided with an annular groove 31 containing a sealing ring 32 adapted to engage the upper edge of the valve seat 17. The sealing ring 32 is retained in the groove 31 by a clamping member 33. The valve stem 21 has threaded portions as indicated at 34 and 35 and nuts 36 are threaded upon said portions and clamp the followers 28 and 29, the circular member 30 and the clamping member 33 in place upon said valve stem.

The boss 26 on the cover member C has a threaded opening 40 adapted to receive one end of a plug 41. The plug 41 is internally threaded as indicated at 42 for the reception of a travel limiting screw 43, the lower portion of which is threaded and the upper portion of which is plain and slotted so that it can be turned by a screwdriver. The plug 41 is counterbored as indicated at 44 and packing 45 is received in said counterbore in surrounding relation to the plain portion of the limiting screw 43. A packing gland 46 is arranged to compress the packing 45 into sealing engagement with said plain portion of the limiting screw 43 to form a seal against leakage. A cap 47 is slipped over the upper end of the limiting screw 43 and engages the gland 46. The cap 47 engages threads 48 formed upon the exterior of the plug 41, whereby the gland 46 can be forced downwardly and held in place to compress the packing 45.

The purpose of the screw 43 is to limit the upward movement of the valve stem 21 and thus limit the extent of opening of the non-surge valve 3. The non-surge valve 3 is thus adaptable for use with pumps of varying capacity, inasmuch as it will be apparent that if said valve is permitted to open to such an extent that the flow therethrough is equal to the capacity of the pump 1, no substantial fluid pressure can be built up between the non-surge valve 3 and the pump 1. Hence, by setting the limiting screw 43 in accordance with the capacity of the pump 1, the non-surge valve 3 can be adjusted to limit its extent of opening so that a suitable back-pressure will be developed to effect closing of the main valve, as will be explained more fully hereinafter.

The cover member C is provided with a main diaphragm chamber 50 adapted to receive operating fluid under pressure for actuating the diaphragm D to effect closing of the non-surge valve 3. The operating fluid under pressure is admitted into the chamber 50 through a passageway 51 formed in the boss 26. The admission of operating fluid into the passageway 51 is controlled

by a pressure-responsive device generally indicated by the letter **X** and including a pilot valve **P**, both of which will be described in detail hereinafter.

Operating fluid under pressure for effecting closing of the non-surge valve **3** is derived from the inlet chamber **15** of said valve. Thus, a conduit **52** is connected at one end thereof to the body **B** as indicated at **53** and the opposite end of said conduit is connected as indicated at **54** to the housing **55** of the pilot valve **P**. The conduit **52** includes a conventional needle valve **56** for controlling the rate of flow of operating fluid to a pressure chamber **57** in the pilot valve housing **55**. A pilot disc **58** is received in the pressure chamber **57** and the lower face thereof seats upon a base member **59** which forms a closure for the pressure chamber **57**. A pilot drive shaft **60** carries a drive washer **60a** having pins **60b** received in apertures **60c** in the pilot disc **58** for effecting rotation of said pilot disc.

The pilot disc **58** includes a U-shaped exhaust passageway **61**, one leg of which registers with a port **62** in the base **59** and the other leg of which registers with an axial port **63** formed in said base. As will be apparent from Fig. 2, when the exhaust passage **61** interconnects the ports **62** and **63** in the base **59**, operating fluid can be exhausted from the diaphragm chamber **50** through a conduit **64** which interconnects the passage **51** and the port **62** and a drain conduit **65** which communicates with the port **63**.

The pilot disc **58** is also provided with a through-passage **66** (see Figs. 3 and 4), which when placed in registration with the port **62** will permit operating fluid under pressure to flow through the conduit **64** and the passage **51** into the diaphragm chamber **50** to effect closing of the non-surge valve **3**. The through-passage **66** and the exhaust passage **61** are positioned on radii at an angle of about 60° to each other so that it is only necessary to rotate the pilot shaft **60** through an angle of 60° to position said passages of the pilot disc **58** to effect either opening or closing of the main valve **3**. The rotation of the pilot shaft **60** through the necessary angle is effected by the pressure-responsive device **X** which will now be described.

The pressure-responsive device **X** includes a casing **69** provided with a chamber **70** and a cover plate **71** which forms a closure for said chamber. The upper end of the pilot shaft **60** projects into the chamber **70** and through the cover plate **71**. A pinion **72** is secured against rotation relative to the shaft **60** by any conventional means. The teeth on the pinion **72** are engaged with ridges **73** formed upon a reciprocable rod **74**. The ridges **73** convert a portion of the rod **74** into a rack effective to impart turning movement to the pinion **72** and the pilot disc shaft **60** which is secured to said pinion.

The rod **74** is supported in the casing **69** in bushings **75** and **76**, as shown in Figs. 2 and 3. One end of the rod **74** carries a circular plate **77** which engages one side of a flexible diaphragm **78**. The diaphragm **78** is marginally secured secured between a flange **79** formed on the casing **69** and a flange **80** formed upon a cover plate **81**, the cover plate **81** being mounted upon the casing **69** by a suitable number of screws **82**.

The casing **69** is also provided with an internally threaded annular flange **83** adapted to receive one end of a pipe nipple **84**. The opposite end of the pipe nipple **84** is received in an internally threaded cap member **85**. A helical com-

pression spring **86** is received within the pipe nipple **84** and one end of said spring rests against a washer **87** mounted upon a shouldered end **88** of the rod **74**. The opposite end of the spring **86** engages a washer **89** abutting against the extremity of an adjusting bolt **90**, threadedly mounted in the cap **85**. The bolt **90** is adapted to be adjusted to vary the compression of the spring **86** and can be locked in any desired position of adjustment by a lock nut **91** arranged to be jammed against the cap **85**.

The function of the spring **86** is to urge the rod **74** to its left-most position as viewed in Fig. 2 so that the pilot disc **58** will normally be in a position with the U-shaped exhaust passage **61** registering with the ports **62** and **63**, whereby the non-surge valve will be permitted to open, the spring **23** urging the valve stem **21** upwardly to displace spent operating fluid from the chamber **50** to effect opening of the valve.

Fluid under pressure for actuating the pressure-responsive device **X** is derived from the inlet chamber **15** of the non-surge valve **3** through a conduit **95**, one end **96** of which is connected with the body **B** and the other end **97** of which is secured to the cover **81** of said pressure-responsive device. A one-way check valve **98** is connected in the conduit **95** to permit a rapid flow of liquid under pressure into a diaphragm chamber **99** formed in the cover **81**. A flap **100** in the check valve **98** prevents a like flow in the opposite direction. However, in the event that a reduced or lower pressure occurs in the inlet chamber **15** fluid can be exhausted from the diaphragm chamber **99** by means of a by-pass **101** formed in the check valve **98**, the flow through the by-pass **101** being controlled by a needle valve **102**. Also, in case a momentary pressure drop occurs in the system, the non-surge valve **3** will not open because the restricted passage **101** prevents sudden release of pressure fluid from diaphragm chamber **99**.

The shifting of the pilot disc **58** from the position shown in Fig. 2 to that shown in Fig. 3 is effected by the application of hydraulic pressure fluid to the diaphragm **78** transmitted through the conduit **95** from the inlet chamber **15** of the non-surge valve **3**. The diaphragm chamber **99** receives the fluid under pressure from the conduit **95** and this pressure fluid causes the diaphragm **78** to flex toward the right thereby effecting shifting of the rod **74** to the right as viewed in Fig. 3.

The adjustment of the spring **86** determines the hydraulic pressure that will be required upon the diaphragm **78** to overcome the force exerted by said spring before shifting of the rod **74** can take place. In any event, the adjustment of the spring **86** is such that the pressure of the air forced through the non-surge valve **3**, should it find its way past the check valve **100** when the pump **1** is started, is insufficient to effect movement of the rod **74** to the right. The movement of the rod **74** toward the right under the influence of hydraulic pressure is limited by the engagement of the plate **77** with the adjacent wall surface of the casing **69**, and the movement of said rod toward the left is limited by the engagement of the washer **87** with the adjacent end wall surface of said casing. Thus, the stroke of the rod **74** is definitely limited in both directions of travel so that the pilot disc **58** is turned to exactly the right angle necessary to position the passages **61** and **66** in cooperating relation with the ports **62** and **63** in the base **59**.

The mode of operation of the non-surge valve 3 in association with the centrifugal pump 1 and the check valve 4 is as follows: When the pump 1 is started, there is no pressure in the piping 2 because normally at such time the non-surge valve 3 is open to the full extent permitted by the adjustment of the limiting screw 43, the spring 23 maintaining said valve in such open positions, as shown in Fig. 2. Upon starting of the pump 1, all of the air in the well casing 1^a is pumped out ahead of the liquid and can escape to the atmosphere through the open non-surge valve 3. However, as soon as the pump 1 begins to lift water or other liquid and the water or other liquid starts to flow through the opening 18 in the non-surge valve 3 a pressure will be built up in the inlet chamber 15 of said valve because the resistance to the flow of liquid through said valve seat opening is greater than the resistance to the flow of air. The amount of back-pressure that will be built up in the inlet chamber 15 will be determined by the capacity of the pump 1 and the extent to which the non-surge valve 3 is permitted to open by the limit screw 43. Obviously, as the pressure builds up in the inlet chamber 15 it will be communicated through the conduit 95 to the diaphragm chamber 99 of the pressure-responsive device X, and when said fluid pressure exceeds the predetermined opposing force offered by the spring 86, said spring will be compressed, the rod 74 shifted to the right and the pilot disc 58 turned from the position shown in Fig. 2 to that shown in Fig. 3 to permit closing of the non-surge valve 3. Simultaneous with the building up of pressure in the inlet chamber 15, operating fluid under pressure will be conducted through the conduit 52 into the pressure chamber 57 of the pilot valve P and will be available to pass through the passage 66 to effect closing of the main or non-surge valve 3 upon shifting of said passage into alignment with the port 62 in the base 59. The needle valve 56 in the conduit 52, of course, will control the rate at which operating fluid under pressure can pass into the pilot disc pressure chamber 57. Hence, the needle valve 56 will control the rate at which the non-surge valve 3 will close, because operating fluid can only be supplied to the main diaphragm chamber 50 at the rate permitted by the adjustment of said needle valve.

Upon closing of the non-surge valve 3 pressure will be gradually built up between the pump 1 and the check valve 4, said pressure eventually overcoming the pressure in the line 7 and effecting opening of the check valve 4 to permit the pumped fluid to pass into the distribution system. A gradual building up of pressure necessarily occurs because of the gradual closing of the non-surge valve 3, it being understood that while said non-surge valve is closing the volume of liquid discharged therefrom gradually diminishes until said valve is closed drip-tight. The gaseous fluid and later the liquid can be discharged from the valve 3 either to the atmosphere into a suitable drain.

After the pump 1 has been shut down, pressure is no longer maintained between said pump and the check valve 4 and the liquid can drain back into the well casing 1^a. This will reduce the pressure in the inlet chamber 15 of the non-surge valve 3 with the result that the pressure in the diaphragm chamber 99 is no longer maintained. The spring 86 then reacts upon the diaphragm 18 through the rod 74 dispelling the spent operating fluid from said chamber and

returning it to the inlet chamber 15 of the valve 3, the return however occurring through the conduit 95 and the by-pass channel 101 in the check valve 98, and the rate of return being controlled by the needle valve 102. When the spent operating fluid has been exhausted from the chamber 99 to an extent sufficient for the rod 74 to have returned to its initial position, the exhaust passageway 61 will be placed in registration with the ports 62 and 63 (see Fig. 3) in the base 59 so that the operating fluid from the main diaphragm chamber 50 of the non-surge valve 3 can then drain through the conduit 64, passage 61 and conduit 65 to the atmosphere thereby permitting said non-surge valve to open. The draining of the spent operating fluid from the main diaphragm chamber 50 is facilitated by the spring 23 which urges the valve stem 21 upwardly to facilitate opening of the main valve and to hold said main valve open in the absence of pressure fluid in said chamber.

Fig. 5 illustrates a modified form of pilot disc 110 which may be substituted in the pilot valve P for the pilot disc 58 presently shown and afford the additional function and advantage of making the non-surge valve serve as a pressure relief valve. The pilot disc 110, as distinguished from the pilot disc 58, includes two U-shaped exhaust passages 111 and 112 instead of one and a single through passage 113. The spacing of the passages 111 to 113 may be upon any desired angle, say about 30°, but is preferably such as not to require excessive shifting of the rod 74 in either direction.

The function of the exhaust passage 112 and the through passage 113 is the same as that of the exhaust passage 61 and the through passage 66. However, the additional exhaust passage 111 will permit the non-surge valve to open again in the event that an excessive hydraulic pressure is built up in the piping 2, particularly if a positive displacement pump is used instead of the centrifugal pump 1.

Fig. 6 illustrates a portion of a modified form of the pressure-responsive device X including a supplemental or relief spring 115, the force of which must be overcome before the non-surge valve 3 can be opened to relieve excess hydraulic pressure. Thus, it will be understood from the hereinabove description of the mode of operation of the pilot valve 58 that closing of the non-surge valve 3 will be effected when the through-passage 113 is aligned with the port 62 in the base 59. Such aligning occurs upon overcoming of the force offered by a spring 86^a, corresponding to the spring 86. In the event that excessive hydraulic pressure is developed in the inlet chamber 15 of the non-surge valve 3, said pressure will be communicated to the diaphragm chamber 99 and tend to move a rod 74^a, corresponding to the rod 74, farther toward the right. One end of the spring 86^a seats upon a washer 87^a carried by a reduced extension 88^a of the rod 74^a. Upon engagement of the washer 87^a with a washer 116 slidably carried upon the extension 88^a, further resistance to said movement of the rod 74^a is presented by the relief spring 115, one end of which is connected to the washer 116, and which spring must be overcome in order to effect opening of the valve 3 to relieve the excess hydraulic pressure developed by the pump 1. Compression of the relief spring 115 and the accompanying shifting movement of the rod 74^a through a predetermined distance will cause rotation of the pilot shaft 60 through an angle sufficient to index the exhaust passage 111

with the port 62 and permit the valve 3 to open and thereby relieve any excess pressure.

The springs 86^a and 115 are adapted to be independently adjusted to respectively determine the pressure at which the valve 3 will close after the pump 1 has started and the pressure at which the valve 3 will automatically open upon the development of excess pump pressure. Thus, the spring 86^a can be adjusted by an externally threaded sleeve 117 mounted in a cap 85^a, similar to the cap 85, and carrying a spring engaging washer 89^a. The sleeve 117 has a hexagonal portion 118 enabling the same to be readily adjusted by a wrench. A lock nut 91^a locks the sleeve 117 in adjusted position relative to the cap 85^a. The sleeve 117 is internally threaded to receive a bolt 119 carrying a washer 120 on its inner end engaged with one end of the relief spring 115. A lock nut 121 locks the screw 119 in adjusted position relative to the sleeve 117.

As the excess pressure is being relieved through the valve 3, the pressure in the diaphragm chamber 99 also will be relieved and the pilot disc 110 will be returned to a position with the passage 113 aligned with the port 62 and the non-surge valve 3 will automatically close. Upon stopping of the pump a further pressure drop occurs and the pilot disc 110 is returned to its starting position with the exhaust passage 112 aligned with the port 62 thereby permitting the non-surge valve 3 to open in preparation for the next starting cycle of the pump 1. Thus, by using a pilot disc such as the disc 110 the non-surge valve 3 can be made to serve not only as an air vent when the pump 1 is started, but also as a pressure relief valve to prevent the building up of excessive hydraulic pressure between the pump 1 and the service check valve 4.

It will be apparent that various changes may be made in the details of construction of the non-surge valve 3 and its associated control mechanism without departing from the spirit of the invention or the scope of the annexed claims.

I claim:

1. In a liquid pumping system wherein a quantity of gaseous fluid precedes the flow of liquid, the combination of: a pump; a service check valve having its inlet connected with the discharge side of said pump and its outlet in communication with a pipe line; a fluid pressure operable non-surge valve connected with the outlet of said pump; and a pilot valve controlling said non-surge valve arranged to control said non-surge valve to automatically vent said gaseous fluid to the atmosphere when said pump is started to preclude said gaseous fluid from getting past said service check valve and into said pipe line and to effect the building up of sufficient hydraulic back pressure to cause flow through said service check valve after said pump has started to pump said liquid.

2. Pumping apparatus for pumping liquid from a well or the like wherein the flow of liquid is preceded by a quantity of air, comprising: a pump; a one-way check valve; a non-surge valve, each of said valves having an inlet chamber connected with the outlet of said pump; and control means for said non-surge valve, said control means including pilot valve means for controlling said non-surge valve in response to a predetermined hydraulic pressure on the inlet side of said non-surge valve to effect closing of said non-surge valve, said check valve being arranged to open upon closing of said non-surge valve.

3. In a liquid pumping system wherein a quan-

tity of gaseous fluid precedes the flow of liquid, the combination of: a pump; a service valve; a non-surge valve, said service valve and said non-surge valve being connected with the outlet of said pump; and automatic control means independent of said non-surge valve for controlling said non-surge valve, said automatic control means being arranged to permit said non-surge valve to remain open while said gaseous fluid is being pumped through said non-surge valve and to effect closing of said non-surge valve when said pump starts to pump said liquid through said non-surge valve.

4. In a liquid pumping system wherein a quantity of gaseous fluid precedes the flow of liquid, the combination of: a pump; a service valve; a non-surge valve, said service valve and said non-surge valve being connected with the outlet of said pump; and automatic control means for said non-surge valve, said automatic control means including pilot valve means arranged to permit said non-surge valve to remain open while said gaseous fluid is being pumped through said non-surge valve and to effect closing of said non-surge valve when said pump starts to pump said liquid through said non-surge valve, said pilot valve means further being arranged to allow opening of said non-surge valve after said pump has stopped pumping said liquid.

5. In a liquid pumping system wherein a quantity of gaseous fluid precedes the flow of liquid, the combination of: a deep well pump; a service valve; a non-surge valve; and automatic control means for said non-surge valve, said service valve and said non-surge valve each having an inlet chamber communicating with the outlet of said pump and hence subject to the pressure developed by said pump, said service valve having an outlet chamber adapted to be connected with a pipe line and said non-surge valve having an outlet chamber communicating with the atmosphere, said automatic control means including a pressure-responsive pilot valve device operated by hydraulic pressure built up on the inlet side of said non-surge valve by said pump, said automatic control means being arranged to permit said non-surge valve to remain open while said gaseous fluid is being pumped through said non-surge valve and to effect gradual closing of said non-surge valve when said pump starts to pump said liquid through said non-surge valve.

6. In a liquid pumping system wherein a quantity of air precedes the flow of liquid, the combination of: a pump; a service check valve connected with the outlet of said pump; a service pipe connected with said service check valve; and means for venting said air pumped by said pump to the atmosphere to prevent its introduction into said service pipe, said means including a vent valve having an inlet chamber in communication with the outlet of said pump, said vent valve having a pressure chamber for operating fluid; and control means for controlling the exhaust of operating fluid from and the admission of operating fluid into said pressure chamber for effecting the opening and closing, respectively, of said vent valve in accordance with changes in the hydraulic pressure in said inlet chamber of said vent valve.

7. In a liquid pumping system wherein a quantity of air precedes the flow of liquid, the combination of: a pump; an automatic check valve; a hydraulically operable non-surge valve, said check valve and non-surge valve each having an inlet chamber in communication with the out-

11

let of said pump, said check valve having an outlet chamber adapted to be connected with a service pipe and said non-surge valve having an outlet chamber communicating with the atmosphere; and automatic control means for said non-surge valve, said automatic control means including pressure-responsive pilot valve means for controlling the admission and exhaust of operating fluid to and from said hydraulically operable non-surge valve and being operable by changes in hydraulic pressure built up on the inlet side of said non-surge valve by said pump, said non-surge valve normally being open when said pump is idle, said control means being arranged to permit said non-surge valve to remain open while air is being pumped through said non-surge valve and to effect closing of said non-surge valve when said pump starts to pump liquid through said non-surge valve, said check valve normally being closed while said pump is pumping air but being arranged to open automatically upon the closing of said non-surge valve and the building up of sufficient hydraulic pressure in the inlet chamber of said check valve to overcome the opposition to flow offered by said check valve.

8. In a water pumping system wherein a quantity of air precedes the flow of water, the combination of: a pump; a service valve; a non-surge valve; and automatic control means for said non-surge valve, said service valve and said non-surge valve each having an inlet chamber communicating with the outlet of said pump and hence subject to the pressure developed by said pump, said automatic control means being pressure-responsive and connected with said inlet chamber of said non-surge valve so as to be operated by hydraulic pressure built up in the inlet chamber of said non-surge valve by said pump, said automatic control means being arranged to permit said non-surge valve to remain open while said air is being pumped through said non-surge valve and to effect closing of said non-surge valve when said pump starts to pump said water through said non-surge valve, said non-surge valve including adjustable means for limiting the extent of opening thereof so as to assure building up of hydraulic back-pressure in said inlet chamber, said service valve normally being closed while said pump is pumping said air but being adapted to be opened upon the closing of said non-surge valve.

9. In a liquid pumping system wherein a quantity of gaseous fluid precedes the flow of liquid, the combination of: a deep well centrifugal pump; a check valve; a non-surge, hydraulic-pressure responsive valve having a pressure chamber for operating fluid, said check valve and said non-surge valve each having an inlet chamber in communication with the outlet of said pump and hence subject to the pressure developed by said pump; and a pressure-responsive control device subject to the pressure developed by said pump arranged to control the exhaust and admission of operating fluid to said pressure chamber so that said non-surge valve is open to the atmosphere when said pump is idle to permit said gaseous fluid to be pumped therethrough when said pump is started and is caused to close when said pump starts to pump said liquid and builds up a predetermined hydraulic pressure in said inlet chamber of said non-surge valve, said check valve normally being closed when said pump is idle but being arranged to open automatically upon the closing of said non-surge valve and the building

12

up of sufficient hydraulic pressure by said pump to overcome the opposition to flow offered by said check valve.

10. In a liquid pumping system wherein a quantity of gaseous fluid precedes the flow of liquid, the combination of: a pump; a service check valve; a non-surge valve, said service check valve and non-surge valve each having an inlet chamber in communication with the outlet of said pump, said non-surge valve having an outlet chamber communicating with the atmosphere and said service check valve having an outlet chamber adapted to communicate with a service pipe line; and automatic control means for said non-surge valve, said automatic control means including pilot valve means arranged to control the opening and closing of said non-surge valve in accordance with changes in hydraulic pressure on the inlet side of said non-surge valve, said service check valve being arranged to open automatically upon the closing of said non-surge valve and the building up of a predetermined hydraulic pressure on said inlet side of said service check valve.

11. In a liquid pumping system wherein a quantity of air precedes the flow of liquid, the combination of: a centrifugal pump; a check valve; a non-surge valve including a pressure chamber for operating fluid; and automatic control means for said non-surge valve, said check valve and said non-surge valve each having an inlet chamber communicating with the outlet of said pump, said automatic control means also communicating with the inlet chamber of said non-surge valve and being pressure-responsive and operable by hydraulic pressure built up in the inlet chamber of said non-surge valve by said pump to control the admission and exhaust of operating fluid from the pressure chamber of said non-surge valve, said non-surge valve normally being open when said pump is idle, said control means being arranged to permit said non-surge valve to remain open while said air is being pumped through said non-surge valve and to effect closing of said non-surge valve when said pump starts to pump said liquid through said non-surge valve, said check valve normally being closed while said pump is pumping said air but being arranged to open automatically upon the closing of said non-surge valve and the building up of a sufficient hydraulic pressure in the inlet chamber of said check valve to overcome the resistance to flow offered by said check valve.

12. In a liquid pumping system wherein a quantity of air precedes the flow of liquid, the combination of: a centrifugal pump; a check valve; a non-surge valve; and automatic control means for said non-surge valve, said check valve and said non-surge valve each having an inlet chamber communicating with the outlet of said centrifugal pump, said automatic control means being arranged to control the opening and closing of said non-surge valve in accordance with the hydraulic pressure changes in the inlet chamber of said non-surge valve, said automatic control means being adjustable to vary the maximum hydraulic pressure at which closing of said non-surge valve is effected.

13. In a liquid pumping system wherein a quantity of air precedes the flow of liquid, the combination of: a pump; an automatic check valve; a non-surge valve; and automatic control means independent of said non-surge valve for controlling said non-surge valve, said check valve and said non-surge valve having inlet chambers com-

municating with the outlet of said pump, said automatic control means being pressure-responsive and operable by hydraulic pressure built up in the inlet chamber of said non-surge valve by said pump, said non-surge valve normally being open when said pump is idle, said control means being arranged to permit said non-surge valve to remain open while said air is being pumped through said non-surge valve and to effect closing of said non-surge valve when said pump starts to pump said liquid through said non-surge valve, said check valve normally being closed while said pump is pumping said air but being arranged to open automatically upon the closing of said non-surge valve and the building up of sufficient hydraulic pressure in the inlet chamber of said check valve to overcome the resistance to flow offered by said check valve; and means in said non-surge valve tending to maintain said non-surge valve in open condition.

14. In a liquid pumping system wherein a quantity of air precedes the flow of liquid, the combination of: a pump; an automatic check valve; a non-surge valve; automatic control means independent of said non-surge valve for controlling said non-surge valve, said check valve and said non-surge valve having inlet chambers communicating with the outlet of said pump, said automatic control means being pressure-responsive and operable by hydraulic pressure built up in the inlet chamber of said non-surge valve by said pump, said non-surge valve normally being open when said pump is idle, said control means being arranged to permit said non-surge valve to remain open while said air is being pumped through said non-surge valve and to effect closing of said non-surge valve when said pump starts to pump said liquid through said non-surge valve, said check valve normally being closed while said pump is pumping said air but being arranged to open automatically upon the closing of said non-surge valve and the building up of sufficient hydraulic pressure in the inlet chamber of said check valve to overcome the resistance to flow offered by said check valve; and means operatively associated with said control means for governing the rate of closing of said non-surge valve.

15. In a liquid pumping system wherein a quantity of air precedes the flow of liquid, the combination of: a pump; an automatic check valve; a non-surge valve; automatic control means for said non-surge valve, said check valve and said non-surge valve having inlet chambers communicating with the outlet of said pump, said automatic control means being pressure-responsive and operable by hydraulic pressure built up in the inlet chamber of said non-surge valve by said pump, said non-surge valve normally being open when said pump is idle, said control means being arranged to permit said non-surge valve to remain open while said air is being pumped through said non-surge valve and to effect closing of said non-surge valve when said pump starts to pump said liquid through said non-surge valve, said check valve normally being closed while said pump is pumping said air but being arranged to open automatically upon the closing of said non-surge valve and the building up of sufficient hydraulic pressure in the inlet chamber of said check valve to overcome the resistance of flow offered by said check valve; and means operatively associated with said control means for preventing sudden opening of said non-surge valve upon a momentary drop in pressure in the inlet chamber of said non-surge valve.

16. Apparatus for pumping liquid from a well or the like wherein the flow of liquid is preceded by a quantity of air, comprising: a pump; a one-way check valve; a non-surge valve including a diaphragm, said check valve and said non-surge diaphragm valve having inlet chambers in communication with the outlet of said pump, said check valve having an outlet chamber adapted to be connected with a service pipe line and said non-surge diaphragm valve having an outlet chamber communicating with the atmosphere, said non-surge diaphragm valve normally being open to the atmosphere when said pump is idle; and automatic control means for said non-surge diaphragm valve arranged to permit said air to be pumped through said non-surge diaphragm valve when said pump is started and to cause said non-surge diaphragm valve to close gradually when said pump begins to pump liquid through said non-surge diaphragm valve and builds up a back pressure in the inlet chamber of said non-surge diaphragm valve, said control means including a pilot valve, and a pressure-responsive device for actuating said pilot valve, said pressure-responsive device communicating with said inlet chamber of said non-surge diaphragm valve and being operable in accordance with changes in hydraulic pressure in said inlet chamber, said pilot valve having a pressure chamber also communicating with said inlet chamber of said non-surge diaphragm valve and having a pilot disc in said pressure chamber actuatable by said pressure-responsive device for controlling the admission and exhaust of operating fluid to said non-surge diaphragm valve in accordance with variations in hydraulic pressure in said inlet chamber of said non-surge diaphragm valve, said check valve normally being closed when said pump is idle but being arranged to automatically open upon the closing of said non-surge diaphragm valve and the building up of sufficient hydraulic pressure by said pump to overcome the opposition to flow offered by said check valve.

17. Apparatus for pumping liquid from a well or the like wherein the flow of liquid is preceded by a quantity of air, comprising: a pump; a one-way check valve; a hydraulically operable non-surge valve, said check valve and said non-surge valve having inlet chambers in communication with the outlet of said pump, said check valve having an outlet chamber adapted to be connected with a service pipe line and said non-surge valve having an outlet chamber communicating with the atmosphere, said non-surge valve normally being open to the atmosphere when said pump is idle; and automatic control means for said non-surge valve arranged to permit air to be pumped through said non-surge valve when said pump is started and to cause said non-surge valve to close gradually when said pump begins to pump liquid through said non-surge valve and builds up a back pressure in the inlet chamber of said non-surge valve, said control means including a pilot valve, a pressure-responsive device for actuating said pilot valve, a conduit connecting said pressure-responsive device with said inlet chamber of said non-surge valve, whereby said pressure-responsive device is rendered operable in accordance with changes in hydraulic pressure in said inlet chamber, said pilot valve having a pressure chamber, a conduit for operating liquid under pressure connecting said pressure chamber with said inlet chamber of said non-surge valve, and a ported pilot disc in said

15

pressure chamber actuatable by said pressure-responsive device for controlling the admission and exhaust of said operating liquid to said non-surge valve in accordance with variations in hydraulic pressure in said inlet chamber of said non-surge valve, said check valve normally being closed when said pump is idle but being arranged to automatically open upon the closing of said non-surge valve and the building up of sufficient hydraulic pressure by said pump to overcome the opposition to flow offered by said check valve.

18. Apparatus as defined in claim 17, in which the conduit connecting the inlet chamber of the hydraulically operated non-surge valve with the pressure responsive device includes a one-way bleeder check valve for preventing sudden opening of said non-surge valve upon a momentary drop in pressure in said inlet chamber.

19. Apparatus as defined in claim 17, in which a needle valve is associated with the pilot valve to control the rate at which the hydraulically operable non-surge valve is closed.

20. Pumping apparatus for pumping liquid from a well or the like wherein the flow of liquid is preceded by a quantity of gaseous fluid, comprising: a pump; a service valve; a non-surge valve, each of said valves having an inlet chamber communicating with the outlet of said pump; and control means for said non-surge valve, said control means being arranged to permit said non-surge valve to remain open so long as said air is being pumped therethrough, to effect closing of said non-surge valve upon the pumping of liquid therethrough, and to again permit opening of said non-surge valve in the event of excessive hydraulic pressure on the inlet side of said non-surge valve.

21. In a water pumping system wherein a quantity of air precedes the flow of water, the com-

5
10

bination of: a pump; a service valve; a non-surge valve; and automatic control means independent of said non-surge valve for controlling said non-surge valve, said service valve and said non-surge valve each having an inlet chamber communicating with the outlet of said pump and hence subject to the pressure developed by said pump, said automatic control means being pressure-responsive and connected with said inlet chamber of said non-surge valve so as to be operated by hydraulic pressure built up in the inlet chamber of said non-surge valve by said pump, said automatic control means being arranged to permit said non-surge valve to remain open while said air is being pumped through said non-surge valve and to effect closing of said non-surge valve when said pump starts to pump said water through said non-surge valve, said service valve normally being closed while said pump is pumping said air but being adapted to be opened upon the closing of said non-surge valve.

DONALD G. GRISWOLD.
